United States Patent Office

Des. 222,158
Patented Oct. 5, 1971

222,158

SKATE BOARD

Chrespin W. Noches, 336 Mar Vista Ave.,
Pasadena, Calif. 91106

Filed June 1, 1970, Ser. No. 23,222

Term of patent 14 years

Int. Cl. D21—01

U.S. Cl. D34—15

FIG. 1 is a plan view of the skate board showing my new design;

FIG. 2 is a left side elevational view of FIG. 1, the right side being a mirror image thereof; and

FIG. 3 is a bottom plan view thereof; and

FIG. 4 is a front elevational view thereof taken perpendicular to the longitudinal line of the skate board.

I claim:

The ornamental design for a skate board, as shown and described.
